5 Claims

ABSTRACT OF THE DISCLOSURE

Compounds of the formula

wherein R¹ and R² can be the same or different and are selected from the group consisting of hydrogen, alkyl of 1-6 carbon atoms and hydroxy alkyl of 1-6 carbon atoms; Y is selected from the group consisting of and

—CH₃, —CH₂Hal, —CHHal₂, —CHHal₃, Hal, —OR, —SR and

wherein Hal is a halogen atom, preferably chlorine, R is selected from the group consisting of hydrogen, alkyl of 1-6 carbon atoms and alkyl of 1-6 carbon atoms substituted by —OH, —OR⁵, —NHR⁵, —N(R⁶)₂ or a halogen atom, R³ and R⁴ have the same significance as R¹ and R² and furthermore may be closed to a ring, possibly with the inclusion of a further heteroatom, such as piperazine, piperidine, phenoxyazine, 9,10-dihydrophenazine or morpholine ring and R⁵ is selected from the group consisting of aryl such as phenyl and alkyl of 1-6 carbon atoms, R⁶ taken individually are aryl or alkyl of 1 to 6 carbon atoms and taken together can be closed to a ring with the nitrogen atom, possibly with inclusion of a further heteroatom, as described above with reference to R³ and R⁴ and Z is

wherein R³ and R⁴ have the same significance as above. These compounds have a strong antiphlogistic action upon oral administration.

The invention relates to novel substituted s-triazines and a method for their production.

The compounds concerned are of the formula:

(I)

wherein R¹ and R² can be the same or different and are selected from the group consisting of hydrogen, alkyl

2

of 1-6 carbon atoms and hydroxy alkyl of 1-6 carbon atoms; Y is selected from the group consisting of —CH₃, —CH₂Hal, —CHHal₂, —CHHal₃, Hal, —OR, —SR and

wherein Hal is a halogen atom, preferably chlorine, R is selected from the group consisting of alkyl of 1-6 carbon atoms and alkyl of 1-6 carbon atoms substituted by —OH, —OR⁵, —NHR⁵, —N(R⁶)₂ or a halogen atom, R³ and R⁴ have the same significance as R¹ and R² and furthermore may be closed to a ring, possibly with the inclusion of a further heteroatom, such as a piperazine, piperidine, phenoxyazine, 9,10-dihydrophenazine or morpholine ring and R⁵ is selected from the group consisting of aryl such as phenyl and alkyl of 1-6 carbon atoms, R⁶ taken individually are aryl or alkyl of 1 to 6 carbon atoms and taken together can be closed to a ring with the nitrogen atom, possibly with inclusion of a further heteroatom, as described above with reference to R³ and R⁴, and Z is

wherein R³ and R⁴ have the same significance as above. Preferably, Y is —CH₃, —CH₂Cl, —CHCl₂ or particularly —CCl₃ or also Z.

30 The new compounds can be prepared by saponifying compounds of the formula

(II)

wherein R⁶ is alkyl or hydroxy alkyl of 1-6 carbon atoms or aryl or hydroxy aryl, in the presence of a water miscible organic solvent, especially a lower alkanol, and preferably methanol, and in the presence of about molar quantities of barium hydroxide or sodium hydroxide, potassium hydroxide at a temperature between 0° C. and the boiling point of the solvent, preferably between about 50 and 70° C. to form a compound of Formula I. In the event that Y initially represents the group —CHHal₃, the compound can be reacted with an amine of the formula

55 wherein R³ and R⁴ have the same significance as above to form compounds wherein Y is

60 The latter reaction can, for example, be carried out in the presence of an alkali metal alcoholate, preferably in quantities of 0.1 to about 10 wt. percent at room or raised temperatures. In order to facilitate the reaction it is expedient to use a lower alkanol as solvent. It, however, also is possible to use a sufficient quantity of the amine

70 that the starting triazine dissolves therein. The ratios of the compounds used, for example, can be between 1:5

3

and 1:10. If the amine is a solid substance, it can first be dissolved in a small quantity of an organic solvent, such as, for example, acetone, ethyl acetate, dioxane or alkanols. If desired, the reaction can also be carried out in the presence of catalytic quantities of water or alkali metal hydroxide. The reaction can be carried out at room temperature.

The compounds used as starting materials, for example, can be prepared by the process described in German Pat. 1,189,999.

The compounds according to the invention exhibit biological activity and can be used as herbicides and also, for example, as analgesic and antiphlogistic substances.

The compounds, for example, provide a strong antiphlogistic action on carrageen edema of the rat's paw upon oral administration in dosages of 10-100 mg./kg.

The following table indicates the arrest in carrageen edema of the rat's paw upon oral administration of 30 mg./kg. of several illustrative compounds according to the invention (results in percent of edema arrest as compared to control group) and the acute toxicity of such compounds. The antiphlogistic action investigations were carried out according to the method of Domenjoz and Coll., Arch. Exp. Path., 230, 325 (1957), and the acute toxicity tests were carried out according to the method of Miller & Tainter, Proc. Soc. Exper. Biol. and Med., 57, 261 (1944) with a 24 hour observation period.

TABLE

	Arrest in carrageen edema at 30 mg./kg. dosage, oral, rat, percent	LD ₅₀ , mg./kg., rat, oral, ca.
D 9220	57	2,000
D 9721	50	1,000
D 9722	52	1,000

D 9220=2-trichloromethyl-4-(1-methyl-1-hydroxy)-ethyl-6-morpholino-s-triazine.
 D 9721=2-ethylamino-4-(1-methyl-1-hydroxy)-ethyl-6-piperazino-s-triazine.
 D 9722=2-ethylamino-4-(1-methyl-1-hydroxy)-ethyl-6-piperazino-hydrochloride-s-triazine.

The following examples will serve to illustrate the compounds according to the invention.

EXAMPLE 1

50 g. of 2-trichloromethyl-4-morpholino-6-[α -(carboxy-oxy)- α -methyl-ethyl]-s-triazine were dissolved in 300 ml. of methanol and the solution heated to boiling. 42 g. of Ba(OH)₂·8H₂O were dissolved in 400 ml. of hot methanol and such solution added to the triazine solution over a 3 hour period while the latter was constantly boiled. The triazine solution which initially was clear became cloudy as the saponification proceeded upon addition of the Ba(OH)₂ solution. The reaction mixture was then boiled down without first separating the solids and the residue stirred up with dilute HCl whereupon CO₂ was set free. The water insoluble portion was taken up in methylene chloride. After such solution had been washed neutral it was boiled down. The residue was triturated with water whereupon it crystallized. The yield of 2-trichloromethyl-4-morpholino-6-(α -methyl- α -hydroxy)-ethyl-s-triazine was 18 g. or 43.5% of theory. Its melting point was 72-82° C.

EXAMPLE 2

85 g. of 2-trichloromethyl-4-ethylamino-6-[α -(carboxy-oxy)- α -methyl-ethyl]-s-triazine were dissolved in 300 ml. of methanol and heated to boiling.

72 g. of Ba(OH)₂ were dissolved in 400 ml. of hot methanol and the non-dissolved BaCO₃ filtered off. This solution was then added to the boiling triazine solution over a 3 hour period. The processing thereafter was as in Example 1. 51 g. or a yield 75% of the theory was obtained as the crystalline residue. When recrystallized from ligroin the 2-trichloromethyl-4-ethylamino-6-(α -methyl- α -hydroxy)-ethyl-s-triazine of a M.P. of 80-82° C. was obtained.

4

EXAMPLE 3

100 g. of 2-[α -(carboxy-oxy)- α -methyl-ethyl]-4-ethanolamino-6-trichloromethyl-s-triazine were dissolved in 180 ml. of methanol. Then a solution of 93 g. of Ba(OH)₂·8H₂O in 700 ml. of methanol were added thereto and the mixture heated to reflux with stirring for 1½ hours. The reaction solution was then adjusted to a pH of 5 with concentrated HCl whereby CO₂ was liberated and the solution concentrated under vacuum. The residue was stirred up with water whereby 46.8 g. of pure 2-(α -methyl- α -hydroxy)-ethyl-4-ethanolamino-6-trichloromethyl-s-triazine with 1 mol of H₂O were obtained. Yield 52% of theory, M.P. 69-74° C.

EXAMPLE 4

114 g. of 2-[α -(carbomethoxy-oxy- α -methyl)ethyl]-4-morpholino-6-trichloromethyl-s-triazine (M.P. 90-95° C.) were dissolved in 500 ml. of methanol and a solution of 90 g. of Ba(OH)₂·8H₂O in 750 ml. of methanol added thereto over a 30 minute period. The mixture was then refluxed for 1½ hours. The processing was described in Example 3.

Yield 51 g. of 2-(α -methyl- α -hydroxy)-ethyl-4-morpholino-6-trichloromethyl-s-triazine.

EXAMPLE 5

Analogously the following compounds

- (a) 2-(α -hydroxy- α -methyl)-ethyl-4-(3-methoxypropyl)-amino-6-trichloromethyl-s-triazine (M.P. 41-43° C.)
 (b) 2-(α -hydroxy- α -methyl)-ethyl-4-piperidino-6-trichloromethyl-s-triazine (M.P. 82-87° C.)
 (c) 2-(α -hydroxy- α -methyl)-ethyl-4-(2-hydroxypropyl)-amino-6-trichloromethyl-s-triazine (syrup)

were respectively obtained from

- (a) 2-[α -(carbomethoxy-oxy- α -methyl)ethyl]-4-(3-methoxypropylamino-6-trichloromethyl-s-triazine
 (b) 2-[α -(carbomethoxy-oxy- α -methyl)ethyl]-4-piperidino-6-trichloromethyl-s-triazine
 (c) 2-[α -(carbomethoxy-oxy- α -methyl)-ethyl]-4-(2-hydroxypropylamino-6-trichloromethyl-s-triazine

EXAMPLE 6

77.5 g. of 2-[α -(carbomethoxy-oxy- α -methyl-ethyl)-4-(3-hydroxy)-propylamino-6-trichloromethyl-s-triazine were heated with 145 ml. of thionyl chloride to produce 2-[α -(carbomethoxy-oxy- α -methyl-ethyl)-4-(3-chloropropylamino-6-trichloromethyl-s-triazine, which was not isolated, but processed in the usual manner as a crude product, which was dissolved in 100 ml. of methanol and heated under reflux for 90 minutes with 63 g. of Ba(OH)₂·8H₂O dissolved in 530 ml. of methanol. After processing as described above, 34 g. or 54% of theory of 2-(α -hydroxy- α -methyl)-ethyl-4-(3-chloropropylamino-6-trichloromethyl-s-triazine of a M.P. of 68-71° C. were obtained.

EXAMPLE 7

41.25 g. of 2-[α -(carboethoxy-oxy- α -methyl-ethyl)-4-piperazino-6-trichloromethyl-s-triazine (0.1 mol) were heated to reflux with 161.6 g. (1.8 mols) 50 P.C. aqueous ethylamine for 4 hours.

The reaction solution was then concentrated under vacuum and the residue dissolved in 200 ml. of methylene chloride. The solution was washed with water to extract the residue of ethylamine. Then the solution had been concentrated under vacuum. The residue yielded 22.3 g. of 2-[α -(carboethoxy-oxy- α -methyl-ethyl)-4-piperazino-6-ethylamino-s-triazine which was 66% of theory. Its melting point was 94-97° C.

EXAMPLE 8

33.8 g. of 2-[α -(carboethoxy-oxy- α -methyl-ethyl)-4-piperazino-6-ethylamino-s-triazine (0.1 mol) were dissolved in 500 ml. of methanol and then a solution of 10 g. of

sodium hydroxyl in 50 ml. water was added. After keeping at room temperature for two days the solid Na_2CO_3 formed was separated and the solution concentrated under vacuum. The residue was dissolved with 200 ml. of ethyl acetate and after washing with water the solution was boiled down.

The residue yielded 20.75 g. of 2-(α -methyl- α -hydroxy)-ethyl-4-piperazino-6-ethylamino-s-triazine which was 78% of theory. Its melting point was 88-92° C.

EXAMPLE 9

26.6 g. of 2-(α -methyl- α -hydroxy)-ethyl-4-piperazino-6-ethylamino-s-triazine (0.1 mol) were dissolved in 200 ml. of ethyl acetate and 3.65 g. of gaseous HCl (0.1 mol) were introduced. The formed solid of hydrogenchloride of the triazine compound was separated and washed with ethyl acetate and thereafter dried.

The yield of 2-(α -methyl- α -hydroxy)-ethyl-4-piperazino-6-ethylamino-s-triazine - hydrogenchloride was 25.6 of 84.6 % of theory. Its melting point under decompositi- 20
tion was 281-85° C.

EXAMPLE 10

36.2 g. of 2-[α -(carbethoxy-oxy)- α -methyl-ethyl]-4-N'-methyl-piperazino-6-ethylamino-s-triazine (0.1 mol, viscous, produced according to Example 7 from 2-(α -carbethoxy-oxy- α -methyl-ethyl)-4-N'-methyl-piperazino-6-ethylamino-s-triazine (0.1 mol, viscous, produced accord-

ing to Example 7 from 2-(α -carbethoxy-oxy- α -methyl)ethyl - 4 - N' - methyl - piperazino - 6 - trichloromethyl - s - triazine, melting point 95-98°) were dissolved in 500 ml. of methanol and refluxed with 31.5 g. of $\text{Ba}(\text{OH}_2 \cdot 8\text{H}_2\text{O}$ (0.1 mol) for two hours. After cooling down 7.3 g. of gaseous HCl (0.2 mol) was added whereupon CO_2 was set free. The solution was concentrated and the residue heated with 200 ml. of ethanol for two hours whereupon the saponified triazine compound was dissolved. The solid BaCl_2 was separated and the solution concentrated under vacuum. The residue was washed with water and dried.

The yield of 2-(α -methyl-hydroxy)-ethyl-4-N'-methyl-piperazino-6-ethylamino-s-triazine was 20.1 g. (95%) or 15 71.8% of theory. Its melting point is 95-99° C.

The following table gives the formulae of the starting materials and products of the examples. For sake of simplicity, the triazine ring

will be represented therein by the symbol

I claim:

1. A substituted s-triazine of the formula

wherein each of R^1 and R^2 are selected from the group consisting of hydrogen, lower alkyl of 1 to 6 carbon atoms and lower hydroxy alkyl of 1 to 6 carbon atoms, Y is selected from the group consisting of

$-\text{CH}_3$, CH_2Hal , $-\text{CHHal}_2$, $-\text{CH}_2\text{Hal}_2$, $-\text{Hal}$, $-\text{OR}$, $-\text{SR}$ and

wherein R is selected from the group consisting of hydrogen, lower alkyl of 1 to 6 carbon atoms and lower alkyl of 1 to 6 carbon atoms substituted with a substituent selected from the group consisting of $-\text{OH}$, $-\text{OR}^5$, $-\text{NHR}^5$, $-\text{N}(\text{R}^6)_2$ and Hal , Hal signifies a halogen atom, R^3 and R^4 have the same meaning as R and may be the same or different with the proviso that only one of these two radicals shall be said substituted alkyl and wherein R^3 and R^4 together may form cyclohexyl, piperazino, N' -methyl-piperazino or piperidino, R^5 is selected from the group consisting of phenyl and lower alkyl of 1 to 6 carbon atoms, R^6 is selected from the group consisting of

wherein R^3 and R^4 have the same significance as above; and their pharmaceutically acceptable acid addition salts.

2. The substituted s-triazine of claim 1 which has the formula

wherein $\text{X}=\text{N}-$ is selected from the group consisting of

in which each of R^3 and R^4 are selected from the group consisting of hydrogen, lower alkyl of 1 to 6 carbon atoms and lower alkyl of 1 to 6 carbon atoms substituted by a member selected from the group consisting of

is selected from the group consisting of piperazine and piperidino nuclei, and each of R^1 and R^2 is a lower alkyl of 1 to 6 carbon atoms.

3. The compound according to claim 1, 2-ethylamino-4- N' -methyl piperazino - 6-(α -methyl- α -hydroxy)-ethyl-s-triazine.

4. The compound according to claim 1, 2-ethylamino-4-piperazino-6-(α -methyl- α -hydroxy)-ethyl-s-triazine.

5. The compound according to claim 1, 2-ethylamino-4-piperazino-6-(α -methyl- α -hydroxy)-ethyl-s-triazine hydrochloride.
